WILLIAM C. BIBB Inventor

By *Richard B. Owen* Attorney

UNITED STATES PATENT OFFICE.

WILLIAM C. BIBB, OF LOUISA, VIRGINIA.

CHECK BOOK.

Application filed June 23, 1925. Serial No. 39,111.

To all whom it may concern:

Be it known that I, WILLIAM C. BIBB, a citizen of the United States, residing at Louisa, in the county of Louisa and State 5 of Virginia, have invented certain new and useful Improvements in Check Books, of which the following is a specification.

This invention appertains to novel means for holding checks and their stubs within 10 a suitable back or cover, so that the stubs can be readily removed from the cover, when all of the checks have been used, to permit a new group or pad of checks to be associated therewith.

15 The primary object of the present invention is to provide a novel check book embodying a back with the checks or stubs loosely mounted therein and held in place at one corner by a stud of novel construction, 20 so as to permit the stubs to be readily swung to one side of the cover, to permit the underlying stubs to be easily filled in with the desired data.

Another object of the invention is to provide 25 novel means for engaging the check stubs so as to normally prevent swinging movement of the said stubs out of the back.

A further object of the invention is to provide 30 a novel check book having a stud carried by one corner of the cover thereof for receiving the check stubs, and novel means mounted upon the stud for preventing displacement of said stubs but permitting a swinging movement thereof to one 35 side of the book, means being provided at another corner of the cover of the book for normally preventing swinging movement of the said stubs and the checks carried thereby.

A further object of the invention is to 40 provide a novel check book embodying a back, and novel means for detachably associating a pad or a sheaf of checks and stubs detachably with the back, the means permitting the check stubs to be moved to one 45 side of the back to permit the convenient filling in of the other stubs when necessary.

A still further object of the invention is to provide 50 a novel check book of the above character, which will be durable and efficient in use, one that will be simple and easy to manufacture and one which can be placed upon the market at a reasonable cost.

With these and other objects in view, the invention consists in the novel construction, 55 arrangement and formation of parts, as will be hereinafter more specifically described,

claimed and illustrated in the accompanying drawings, in which drawings:

Figure 1 is a perspective view of a check book constructed in accordance with this 60 invention,

Figure 2 is a perspective view of a check book constructed in accordance with this invention, showing one of the covers thereof in open position to display the checks 65 and stubs to view,

Figure 3 is a detail view of the inner face 70 of one cover of the check book back showing the novel means associated therewith for receiving and holding the checks and stubs, the means for holding the checks and stubs against normal swinging movement being shown in section,

Figure 4 is a detail section taken on the line 4—4 of Figure 3 looking in the direction of the arrows, illustrating the novel 75 means employed for holding the checks and stubs in position on the back and for permitting swinging movement of the stubs to facilitate the filling in of the stubs,

Figure 5 is a detail perspective view of 80 the novel stud bolt utilized for holding the checks and stubs on the back,

Figure 6 is a detail perspective view of 85 the clip utilized for normally preventing swinging movement of the check and stubs on the said stud bolt,

Figure 7 is a detail section taken on the line 7—7 of Figure 3 looking in the direction of the arrows, showing the clip for preventing 90 normal swinging movement of the said checks and stubs,

Figure 8 is a detail section taken on the line 8—8 of Figure 3 showing the novel 95 means employed for holding the clip in position on the said book back,

Figure 9 is a perspective view of a slightly modified form of the check book.

Referring to the drawings in detail, 100 wherein similar reference characters designate corresponding parts throughout the several views, the letter A generally indicates the improved check book, which can be of any desired size for holding a single row of checks and stubs or a plurality of rows of checks and stubs. As shown in the drawings, the check book is of a size for receiving two rows of checks.

The novel check book A comprises a back 10 including the covers 11 and 12 connected together by a suitable flexible binding strip 13. The cover 10 is adapted to receive a

plurality of leaves 14 which are perforated and clinched over the same as at 23. The and printed to provide checks 15 and stubs 16. The leaves 14 are detachably connected with the back in a novel manner as will be now described and in view of the fact that when all of said leaves have been used, a new set of leaves can be used with the back, it can be seen that the back can be repeatedly used, which greatly diminishes the cost of the book. This gives the bank an opportunity to furnish their customers a relatively high grade of back and then only furnish the customers with unbound sheaves of checks when needed.

15 In accordance with this invention I provide means 18 carried by one corner of the cover 10 for holding the leaves in position and this means 18 is so constructed as to allow turning movement of the stub portions 16 of the leaves after the checks have been written to one side of the lowermost stub to facilitate the filling in of the desired data thereon. This is a decided improvement over the old type of check book, in which it is necessary to pull back and hold the stubs in an elevated position when a new stub is being filled out.

This means 18 embodies a cylindrical stud 19 carried by a thin disk shaped plate 20. The stud 19 is adapted to be inserted at one corner of the back, for instance the outer upper corner of the cover 11 until the thin disk shaped plate 20 comes in contact with the outer face of the cover. Any means can

35 be provided for holding the thin disk shaped plate 20 in position on the cover, and as shown therein in spaced relation to the first group of holes 27 which permits the stubs to be readily placed upon a file after the stubs 21 which can be forced through the back 11, have been all filled in and removed from the said cover.

40 Changes in details may be made without departing from the spirit or scope of this invention, but:

What I claim as new is:

1. In a check book, a cover having a back, a plurality of checks arranged on the bank having stubs, means for pivotally connecting the check stubs on the back including a stud bolt extending through one corner of the cover, a relatively thin disk shaped plate formed on one end of the stud bolt connected with the back, the stud bolt extending through one corner of the check stubs, and a relatively thin nut fitted upon the opposite end of the stud bolt, and a clip carried by the opposite corner of the back for detachably engaging the said check stubs at a point remote from said stud bolt.

2. In a check book, a cover including a back, and a plurality of superimposed leaves arranged on the back perforated and printed to define bank checks and check stubs, edges of said attaching plate can be provided with penetrating tongues 32 which are adapted to be inserted through the cover

check stubs, means rigidly connecting one

end of the stud bolt to the back, detachable means engaging the opposite end of the stud bolt for preventing accidental movement of the check stubs from off of the same, and means for normally preventing the swinging movement of a check stub on the stud bolt including a clip having an attaching plate connected with the back at a point remote

from said bolt, a laterally extending arm formed on one end of the attaching plate for engaging the edges of the check stubs, and a tongue carried by the arm for engaging the outer faces of the stubs. ¹⁰

In testimony whereof I affix my signature.

WILLIAM C. BIBB.
